UNITED STATES PATENT OFFICE

119,187

DESIGN FOR A BADGE

Francis X. Phelan, Medford, Mass.

Application February 27, 1939, Serial No. 83,238

Term of patent 14 years

To all whom it may concern:

Be it known that I, Francis X. Phelan, a citizen of the United States, residing at Medford, in the county of Middlesex and the Commonwealth of Massachusetts, have invented a new, original, and ornamental Design for a Badge, of which the following is a specification, reference being had to the accompanying drawing, forming part thereof.

I claim:

The ornamental design for a badge, as shown.

FRANCIS X. PHELAN.
